UNITED STATES PATENT OFFICE.

EDWARD ALFRED GRAHAM, OF BROCKLEY, ENGLAND; MARIA GRAHAM AND ALFRED GRAHAM EXECUTORS OF SAID EDWARD ALFRED GRAHAM, DECEASED.

HORN, TRUMPET, OR LIKE ACOUSTIC AMPLIFIER.

Application filed October 18, 1924, Serial No. 744,513, and in Great Britain January 18, 1924.

This invention relates to a horn, trumpet or like acoustic amplifier for use with loud speaking telephonic receivers and other sound producing or reproducing apparatus, and it has for its object to produce an acoustic amplifier of the kind referred to (hereinafter referred to as a horn) that shall provide the maximum acoustic amplification consistent with the form or development of the horn, and at the same time allow of an ornamental or artistic exterior finish being imparted to the horn.

In acoustic amplifiers applied to apparatus in which sound waves are produced or originated by the vibration of a diaphragm, as in the case of an electro-magnetic telephonic receiver, it is usual to employ a horn of gradually increasing cross sectional area or capacity from the sound chamber containing the vibratory diaphragm to its outer extremity which generally develops into a bell mouth.

Such horns whether of straight, bent or curved outline and whether made in one or several parts or sections jointed together, are frequently heavily coated and lined with an enamel which imparts an appearance simulating a coarse and cross grained leather-known as Levant grain. This enamel, in addition to imparting an artistic effect or finish, sometimes called a crackle or crystalline surface, to the horn, also possesses further advantages inasmuch as, owing to its forming a comparatively thick layer and to its irregular finish it conceals blemishes produced in the horn during manufacture thereof whilst owing to its being of a semi-elastic character, it produces a sound deadening effect tending to reduce resonance in the thin metal or other substance of which the horn is made. The lining of a horn with enamel of the kind referred to (hereinafter called for distinction sound deadening enamel) does however prejudicially affect the free development of sound waves passing through the portion of the horn of gradually increasing diameter, extending from its inlet end to its junction with the bell mouth end, and consequently the clarity of the resulting sounds.

Now according to the present invention, in order to retain the advantages of the sound deadening enamel and at the same time avoid its disadvantages, the portion of the horn of gradually increasing diameter and made of metal or other suitable material, instead of being covered both internally and externally with the sound deadening enamel, has its exterior portion, or part thereof, covered with such enamel whilst its interior portion is covered with a plain enamel having a clean and smooth finish so that a surface free from inequalities and obstructions in the gradually expanding passage of the horn, is obtained that will allow of the free development of the sound waves passing therethrough whilst the coating of sound deadening enamel on the outer surface of the horn imparts an artistic and economical finish with a tendency to minimize resonance in the horn.

An acoustic horn generally develops in cross sectional area in a gradual manner from its inlet end to a point where the flaring or bell mouth end commences and continues more abruptly and it is only necessary to apply to the gradually developing portion of the horn a coating of the enamel having a clean and smooth finish.

By experiment it has been found that a horn lined with enamel adapted to afford a smooth surface and covered externally with a heavier deposit of the sound deadening enamel has an acoustic efficiency—that is to say volume of reproduced sound and clarity thereof—of approximately 20% over and above that of an equivalent horn, treated internally with the said sound deadening enamel in the same manner as the exterior which, as before stated, is the usual practice.

It will be understood that the treatment hereinbefore described constituting the present invention can be applied to sound amplifying horns of any shape whether constructed in one, two or more sections.

In the accompanying drawings, Fig. 1 shows partly in longitudinal section and partly in side elevation and, by way of example only, one construction of horn em- 109

bodying the invention, Fig. 2 being a similar view of another construction of horn.

In the example according to Fig. 1, the horn made of thin sheet material, for instance metal, comprises a straight portion *a* of gradually increasing diameter and a flaring or bell mouthed shaped outlet portion *a'*, the smaller or inlet end of the horn being adapted to be connected to a telephone receiver *b* or other sound producing device. The inner surface of the portion *a* of the horn is lined with a layer of enamel *c* presenting a hard and smooth surface while the outer surface of both portions *a* and *a'* of the horn are coated with a layer of sound deadening enamel *d* of the kind hereinbefore referred to, adapted to afford a coarse cross grained, roughened or crackle surface of the kind mentioned. The inner surface 20 of the bell mouthed portion *a'* of the horn may be lined with enamel of the kind used to line the straight portion *a* of the horn and impart a hard and smooth surface thereto, but it may, if desired, and for the sake of 25 appearance, be lined as shown with sound deadening enamel *d* similar to that applied to the exterior of the horn, as it is only particularly essential to provide a smooth unobstructed and non-sound absorbent layer of 30 enamel *c* to the interior of the longer and gradually tapering portion *a* of the horn.

In Fig. 2 the horn comprises a built up bell mouth portion *e* of non-metallic material for instance wood, which need not be 35 enamelled in any way either internally or externally, the remaining portion *f* of the horn however of gradually increasing diameter from its inlet end being provided with a smooth lining *e* and with an exterior covering 40 having a crackle surface *d* as in the previous example.

In each case, the enamels *c* and *d* are separately applied as layers thereof to the inner and outer surfaces of the horn and 45 are not naturally present thereon as a glaze or roughened surface.

What I claim is:—

1. For a loud speaking telephonic receiver or other sound producing or reproducing apparatus, an acoustic horn-like amplifier comprising a portion of gradually increasing cross sectional area from the end to which a sound producing chamber is to be attached, and a bell mouth of more abruptly increasing cross sectional area, said first mentioned portion having an applied lining of enamel affording a hard smooth surface and an applied exterior coating of sound deadening enamel affording a coarse cross grained, roughened or crackle surface, substantially as described.

2. For a loud speaking telephonic receiver or other sound producing or reproducing apparatus, an acoustic horn-like amplifier comprising a portion of gradually increasing

cross sectional area from the end to which a sound producing chamber is to be attached, and a bell mouth of more abruptly increasing cross sectional area, said first mentioned portion having an applied lining of enamel affording a hard smooth surface and an applied exterior coating of sound deadening enamel affording a coarse cross grained, roughened or crackle surface, and said bell mouth having a coating of like sound deadening material, substantially as described.

3. For a loud speaking telephonic receiver or other sound producing or reproducing apparatus, an acoustic horn-like amplifier comprising a portion of gradually increasing cross sectional area from the end to which a sound producing chamber is to be attached, and a bell mouth of more abruptly increasing cross sectional area, said first mentioned portion having an applied lining of enamel affording a hard smooth surface and an applied exterior coating of sound deadening enamel affording a coarse cross grained, roughened or crackle surface, and said bell mouth having both a coating and lining of like sound deadening material, substantially as described.

4. For a loud speaking telephonic receiver or other sound producing or reproducing apparatus, an acoustic horn-like amplifier comprising a sheet metal portion of gradually increasing cross sectional area from the end to which a sound producing chamber is to be attached, and a bell mouth of more abruptly increasing cross sectional area, said first mentioned portion having an applied lining of enamel affording a hard smooth surface and an applied exterior coating of sound deadening enamel affording a coarse cross grained, roughened or crackle surface, substantially as described.

5. For a loud speaking telephonic receiver or other sound producing or reproducing apparatus, an acoustic horn-like amplifier comprising a sheet metal portion of gradually increasing cross sectional area from the end to which a sound producing chamber is to be attached, and a sheet metal bell mouth of more abruptly increasing cross sectional area, said first mentioned portion having an applied lining of enamel affording a hard smooth surface and an applied exterior coating of sound deadening enamel affording a coarse cross grained, roughened or crackle surface, and said bell mouth having a coating of like sound deadening material, substantially as described.

6. For a loud speaking telephonic receiver or other sound producing or reproducing apparatus, an acoustic horn-like amplifier formed of sheet metal and comprising a portion of gradually increasing cross sectional area from the end to which a sound producing chamber is to be attached, and a bell

mouth of more abruptly increasing cross sectional area, said first mentioned portion having an applied lining of enamel affording a hard smooth surface and an applied exterior coating of sound deadening enamel affording a coarse cross grained, roughened or crackle surface, and said bell mouth having

both a coating and lining of like sound deadening material, substantially as described.

Signed at London, England, this thirteenth day of September, 1924.

EDWARD ALFRED GRAHAM.
